UNITED STATES PATENT OFFICE

109,895

DESIGN FOR AN ESCUTCHEON PLATE FOR RADIO RECEIVER APPARATUS

Richard C. Marholz, Chicago, Ill., assignor to
Belmont Radio Corporation, Chicago, Ill., a
corporation of Illinois

Application March 30, 1938, Serial No. 76,189

Term of patent 7 years

To all whom it may concern:

Be it known that I, Richard C. Marholz, a citizen of the United States, residing at Chicago, in the county of Cook and State of Illinois, have invented a new, original, and ornamental Design for an Escutcheon Plate for Radio Receiver Apparatus, of which the following is a specification, reference being had to the accompanying drawing, forming part thereof, in which:

Figure 1 is a top plan view of the escutcheon plate for radio receiver apparatus showing my new design.

Figure 2 is a front elevational view thereof.

Figure 3 is an end elevational view thereof.

I claim:

The ornamental design for an escutcheon plate for radio receiver apparatus, as shown.

RICHARD C. MARHOLZ.
